CARBURETOR

Paul Xavier Auguste Gistucci, Paris, and Johann Lichtenstein, Levallois-Perret, France, assignors to Societe Generale des Carburateurs Zenith, Levallois-Perret, France, a corporation of Switzerland

Application December 6, 1935, Serial No. 53,188
In France December 6, 1934

9 Claims. (Cl. 261—69)

The present invention relates to carburetors wherein the fuel spray outlet is fed from the fuel chamber of a pressure regulator comprising a diaphragm which closes said chamber and actuates a valve controlling the admission of fuel to said chamber.

One object of the invention is to create in the fuel, at the level of the fuel outlet, a pressure which is independent of the inclinations of the carburetor in any direction.

The invention is particularly concerned with carburetors adapted to acrobatic flying.

One object of the invention is to provide a carburetor comprising a weighted lever adapted to pivot around an axis and connected at one end to the diaphragm of the pressure regulator, preferably at the centre thereof. The distribution of the weight of the lever and the relative position of the lever axis and of the spray outlet are such that a straight line connecting the spray outlet to the centre of the diaphragm is perpendicular to the plane defined by the lever axis and the centre of gravity thereof.

Further objects and advantages will be apparent to those skilled in this art from the following description taken in connection with the accompanying drawings, in which:

Figure 1 is a longitudinal section of a carburetor embodying the invention.

Figure 2 illustrates a geometrical diagram showing the effectiveness of the invention.

Figure 3 is a diagrammatic longitudinal section of another embodiment of the invention.

Referring to Figure 1, there is shown a carburetor in which the mixing chamber 1 is fed with fuel through an outlet 2 receiving liquid fuel (not atomized). By "spray orifice" is meant the point where the fuel, previously in liquid state, is spread in a gaseous atmosphere. The fuel outlet 2 is fed with fuel by a pressure regulator comprising a flexible diaphragm 4. The fuel chamber 3 communicates, through an orifice 6 controlled by a valve 7 connected to the diaphragm 4, with a conduit 5 containing fuel under pressure.

A lever 8 pivoting around an axis 9 engages a bracket 11 fixed to the diaphragm 3. A designates the spray orifice; C the centre of the diaphragm; L the geometrical axis on which lever 8 is pivotally mounted; G the centre of gravity of the lever and O the base of the perpendicular dropped from G to the shaft L.

If the diaphragm is perfectly flexible, that is to say if it does not oppose any resistance to deformations, the diaphragm 4 and the valve 7 assume a position of equilibrium during opera-

tion. For said position, the pressure exerted by the fuel on the face of diaphragm 4 in contact with the fuel, equilibrates the atmospheric pressure exerted on the opposite side of the diaphragm plus the pressure exerted by weighted lever 8 on said diaphragm.

In the absence of lever 8, the fuel pressure on the diaphragm 4 would only have to balance the atmospheric pressure, so that the pressure on the fuel at the centre C of the diaphragm, would be equal to the atmospheric pressure, while the pressure on the fuel at the level of the spray orifice A would be weaker than the atmospheric pressure, the difference between the atmospheric pressure and the pressure at this level being measured by a liquid height equal to the vertical distance between C and A.

If the pressure on the fuel at the level of the spray orifice A is equal to the atmospheric pressure, the liquid column comprised between this spray orifice and the diaphragm exerts on said diaphragm a certain pressure which is to be added to the atmospheric pressure. In order that the pressure at the level of the spray orifice A be equal to the atmospheric pressure, it is thus necessary that lever 8 exert on the diaphragm 4 a pressure which equilibrates the pressure exerted by the liquid column on the diaphragm 4.

The thrust F exerted by the diaphragm 4 on the end 10 of lever 8, under the action of the liquid column, is perpendicular to the diaphragm and proportional to the vertical distance between the spray orifice A and the centre C of the diaphragm. The thrust exerted by the end 10 of lever 8 of the diaphragm by the weight P of the lever is proportional to the moment of said weight about the axis L. Referring to Figure 2, where only the axis L, the centre C of lever 8, the centre G of the diaphragm and the spray orifice A are illustrated for a given inclined position of the apparatus, the moment of weight P with respect to axis L is equal to $GP' \times OG$, wherein GP' designates the projection of the weight P on a perpendicular to the plane defined by the axis L and centre of gravity G.

The vertical distance between the spray orifice A and centre C of the diaphragm is represented by the projection AA' of straight line AC on the vertical.

According to the invention, straight line CA is perpendicular to plane (L, G) and consequently is parallel to straight line GP' . If φ is the angle of the two parallel straight lines GP' and AC with the vertical, the moment of weight P about

the axis L is equal to $GP \times OG \times \cos \varphi$ while the vertical distance AA' is equal to $AC \times \cos \varphi$.

It can thus be seen that the moment of weight P relatively to the axis L and the vertical distance between the spray orifice A and the centre of the diaphragm are both proportional to $\cos \varphi$ and are therefore in a constant ratio whatever be the inclinations of the apparatus. The same is true of the stress exerted by the lever 10 on the diaphragm 4 under the action of weight P and of the thrust F transmitted by the diaphragm 4 to the end 10 under the action of the liquid column. It is therefore merely necessary to choose a proper value for weight P in order that these stresses and thrust be equal for any position of the apparatus and, consequently, in order that the pressure in the fuel at the level of the spray orifice A be equal to the atmospheric pressure, whatever be the position of the apparatus.

In practice, the value which must be given to weight P, in order that this weight equilibrates the liquid column for a given particular position of the carburetor, would be determined by experiment. The realization of the geometrical condition, according to which the straight line CA connecting the centre of the diaphragm to the spraying outlet is perpendicular to the plane determined by the centre of gravity G of the lever 30 and the axis L of this lever, of course necessitates the determination of the centre of gravity G either by experiment or by calculation.

If the spray orifice is located exactly at the level where the fuel pressure is equal to the atmospheric pressure, it may occur that fuel will flow by capillary action when the engine fed by the carburetor stops. According to the invention, in order to obviate this inconvenience, the spray orifice is located slightly above this level 40 when the carburetor is in the normal position, the distance being sufficiently short that the pressure at the level of the spray orifice is substantially independent of the inclinations of the apparatus.

45 In Figure 1, the spray orifice A is shown opening into the mixing chamber of the carburetor. It is obvious that all that has been said concerning Figure 1 would be applicable in case of the discharge orifice A opening into an intermediate 50 atomizing chamber as it is immaterial, so far as the invention is concerned, whether the fuel be mixed to all or to only a portion of the air when issuing from the spray orifice. In all cases, the liquid column which has to be considered terminates at the point where the liquid fuel meets the air and mixes therewith. It is this point 55 which has been designated by spray orifice.

Moreover, it has been assumed that the side of the diaphragm 4 which is not in contact with the fuel is submitted to the atmospheric pressure. This was but an example and it is obvious that the pressure supported by this side of the diaphragm may have any other value.

Also, the diaphragm may be loaded, not only 65 by the weight and the pressure of the gas (air) in contact with it, but also by a spring. This is due to the fact that the pressure exerted by a spring on the diaphragm is independent of the position of the apparatus, so that if the diaphragm is loaded by a spring, the pressure prevailing in the fuel at the level of the spray orifice 70 remains independent of inclination, provided the geometrical conditions and the conditions determining the weight, which have been mentioned 75 above, are fulfilled.

In Figure 3 there is shown a carburetor embodying the invention and in which the fuel chamber 3 feeds a spray orifice A opening into the atomizing chamber 13. The atomizing chamber 13 is fed with air by an orifice 14 and the 5 atomized fuel is delivered into the mixing chamber 1 of the carburetor by a conduit 15.

The diaphragm 4 is loaded both by weight P of lever 8 and by a spring 16. Under these conditions, the spray orifice A is fed under a 10 predetermined pressure and there must be provided a stop member controlling the admission of fuel in order to avoid the fuel flow through the spray orifice A when the engine stops.

According to the invention, the straight line 15 CA connecting the center of the diaphragm to the spray orifice is perpendicular to the plane defined by the axis L and the centre of gravity G of lever 8. Under these conditions, the pressure of the fuel at the level of the spray orifice 20 A is independent of the inclination of the apparatus.

Although the point of connection of the diaphragm to the lever is preferably arranged at the center of the diaphragm, this condition is not 25 obligatory, since the connection may be located at a point other than the centre, but obviously should not be too near the edges of the diaphragm.

What we claim is:

1. In a carburetor, a fuel outlet, a pressure regulator supplying fuel to said outlet and comprising a fuel chamber closed by a diaphragm controlling admission of fuel to said chamber, a weighted lever adapted to pivot around an 35 axis and to be connected at one end to the centre of said diaphragm for balancing the pressure exerted by the column of fuel between the fuel outlet and the center of the diaphragm, the distribution of the weight of said lever and 40 the relative positions of the lever axis and of the fuel outlet being such that a straight line connecting the fuel outlet to the centre of said diaphragm is perpendicular to the plane defined by the lever axis and the centre of gravity of 45 said lever.

2. In a carburetor, a fuel outlet, a pressure regulator supplying fuel to said outlet and comprising a fuel chamber closed by a diaphragm, a valve actuated by said diaphragm for controlling the 50 admission of fuel to said fuel chamber, a weighted lever pivoting around an axis and connected to the centre of the diaphragm, for balancing the pressure exerted by the column of fuel comprised between the fuel outlet and the centre of the diaphragm, a straight line connecting the centre of the diaphragm to the fuel outlet being perpendicular to the plane defined by the lever axis and the centre of gravity of said lever.

3. In a carburetor, a mixing chamber, a fuel outlet in this mixing chamber, a pressure regulator supplying fuel to said outlet and comprising a fuel chamber closed by a diaphragm controlling admission of fuel to said chamber, a weighted lever adapted to pivot around an axis and to be 65 connected at one end to the centre of said diaphragm for balancing the pressure exerted by the column of fuel between the fuel outlet and the centre of the diaphragm, the distribution of the weight of said lever and the relative positions of the lever axis and of the fuel outlet being such that a straight line connecting the fuel outlet to the centre of said diaphragm is perpendicular to the plane defined by the lever axis and the centre of gravity of said lever.

4. In a carburetor, a mixing chamber, a fuel outlet in this mixing chamber, a pressure regulator supplying fuel to said outlet and comprising a fuel chamber closed by a diaphragm, a valve actuated by said diaphragm for controlling the admission of fuel to said fuel chamber, a weighted lever pivoting around an axis and connected to the centre of the diaphragm, for balancing the pressure exerted by the column of fuel comprised between the fuel outlet and the centre of the diaphragm, a straight line connecting the centre of the diaphragm to the fuel outlet being perpendicular to the plane defined by the lever axis and the centre of gravity of said lever. 5
5. In a carburetor, a mixing chamber, an atomizing chamber communicating with the mixing chamber, a fuel outlet in said atomizing chamber, a pressure regulator supplying fuel to said outlet and comprising a fuel chamber closed by a diaphragm controlling the admission of fuel to said fuel chamber, a weighted lever pivoting around an axis and connected to the diaphragm adjacent the centre thereof for balancing the pressure exerted on said diaphragm by the fuel column comprised between the fuel outlet and the centre of the diaphragm, a straight line connecting the fuel outlet to the centre of the diaphragm being perpendicular to the plane defined by the lever axis and the centre of gravity of said lever. 10
6. In a carburetor, a mixing chamber, a fuel outlet in this mixing chamber, a pressure regulator supplying fuel to said outlet and comprising a fuel chamber closed by a spring loaded diaphragm controlling admission of fuel to said fuel chamber, a weighted lever adapted to pivot around an axis and to be connected at one end to the centre of said diaphragm for balancing the pressure exerted by the column of fuel between the fuel outlet and the centre of the diaphragm, the distribution of the weight of said lever and the relative positions of the lever axis and of the fuel outlet being such that a straight line con- 15
- necting the fuel outlet to the centre of said diaphragm is perpendicular to the plane defined by the lever axis and the centre of gravity of said lever. 20
7. In a carburetor, a mixing chamber, an atomizing chamber communicating with the mixing chamber, a fuel outlet in said atomizing chamber, a pressure regulator supplying fuel to said outlet and comprising a fuel chamber closed by a spring loaded diaphragm controlling the admission of fuel to said fuel chamber, a weighted lever pivoting around an axis and connected to the diaphragm adjacent the centre thereof for balancing the pressure exerted on said diaphragm by the fuel column comprised between the fuel outlet and the centre of the diaphragm, a straight line connecting the fuel outlet to the centre of the diaphragm being perpendicular to the plane defined by the lever axis and the centre of gravity of said lever. 25
8. In a carburetor, a mixing chamber, a fuel nozzle positioned to discharge into the mixing chamber, and a pressure regulator supplying fuel to said nozzle and comprising a fuel chamber having a movable wall, a valve connected to said wall and controlling the inflow of fuel to said fuel chamber, a lever pivotally mounted on the carburetor and connected at one end to said wall for balancing the pressure exerted by the column of fuel between the nozzle outlet and the wall, the distribution of the weight of said lever relative to its pivot and to the nozzle outlet being such that a straight line connecting the latter to the center of pressure of said wall is perpendicular to the plane defined by the pivot and the center of gravity of said lever. 30
9. The invention defined in claim 8, wherein a spring yieldingly urges the valve toward its open position. 35
